[57] **CLAIM**

The ornamental design for a fluid cartridge for holding reagents in an automated clinical chemistry analyzer, as shown.

DESCRIPTION

FIG. 1 is a top, right, front perspective view of a fluid cartridge for holding reagents in an automated clinical chemistry analyzer, showing our new design; FIG. 2 is a right side elevational view thereof; FIG. 3 is a top plan view thereof; FIG. 4 is a front elevational view thereof; and FIG. 5 is a rear elevational view thereof; and FIG. 6 is a bottom plan view thereof.

FIG. 1

FIG. 2

FIG. 3

FIG. 4

FIG. 5

FIG. 6
